FREDERIC E. BERTRAND, OF LYNN, MASSACHUSETTS, ASSIGNOR TO UNITED SHOE MACHINERY CORPORATION, OF PATERSON, NEW JERSEY, A CORPORATION OF NEW JERSEY.

MACHINE FOR OPERATING UPON SOLES.

Application filed April 21, 1920. Serial No. 375,600.

This invention relates to machines for use in the manufacture of shoes and is herein illustrated as embodied in a machine for preparing the toe portions of soles for sewing operations.

In making shoes with narrow or peaked toes, considerable difficulty is experienced in sewing together the sole and upper at the toe of the shoe. This is on account of the side-by-side relationship of the channel guide and the feed point in the sewing machine, the sharp curvature of the channel at the extreme point of a peaked-toe sole and the resulting narrowness of the space between the converging outer edges of the channel. These conditions combine to prevent the channel guide and the feed point from following the root of the channel during the process of sewing around the toe of the shoe. As a result the channel flap is mutilated and the between substance may be injured. Furthermore, as the shoe is swung abruptly to effect the rounding of the toe, the raised portion of the sole between the converging inner edges of the channel wipes across the under side of the channel guide. This tends to force the sole downwardly with respect to the channel guide and thus subject the channel flap and the between substance to additional strain, so that they may become weakened to such an extent that the stitches will not hold properly. The seam is then liable to rip before the completion of the shoe. The downward pressure upon the sole also tends to depress the marginal rib to which the upper is to be sewed so as to cause the needle to penetrate the rib in a higher plane around the toe than around the remainder of the sole. This is especially disadvantageous in making turn shoes, as the upper is not drawn down tight against the margin at the base of the rib, a condition which detracts from the appearance of the finished shoe.

One of the objects of the present invention is to provide a machine for preparing soles having peaked toes in such a manner as to insure freedom of relative movement between the channel guide and the sole when op-

erating at the toe during a sole sewing operation.

With this object in view, a feature of the invention consists in the provision of means for removing material from a sole between the converging sides of the channel at the toe without injuring the channel flap, and means to position a sole to be operated upon thereby. It is preferred to employ for the purpose of removing the sole material a cutting tool in the nature of a twist drill which is disposed with its axis normal to the plane of the bottom of the channel and is arranged to rotate continuously during the operation of the machine. The tool operates to enlarge the channel at the toe so as to provide additional clearance space for the channel guide and the feed point of the sewing machine as the shoe is swung abruptly during the operation of sewing around the toe. Associated with the cutting tool is a tubular turning tool for turning back the channel flap to open the channel at the toe of the sole to prevent mutilation of the channel flap and weakening of the between-substance while sewing around the toe of the shoe. The tubular turning tool is preferably arranged to rotate continuously about an axis normal to the plane of the bottom of the channel in the sole and is provided with one or more lateral axially disposed ribs, which are adapted to engage the inner side of the channel flap, as the tool rotates, and to raise the flap to an upright position by a series of rapidly delivered hammer-like blows.

In order that the clearance cutting operation may occur while the channel flap is being turned, without interfering with the operation of the flap-turning tool, a further feature of the invention consists in the mounting of the cutting tool for axial movement within the tubular flap-turning tool and the provision of means for normally maintaining the former in retracted inoperative position and for projecting it into working position with its cutting edge beyond the sole-engaging end of the latter at the will of the operator.

Other objects of the invention and the features of construction by which they are attained, including an improved mounting for co-axial tools so that both of them may be used simultaneously, or one of them alone, and an improved mounting for a drill or similar stock-removing implement to eject the waste cut away thereby, will be set forth hereinafter in connection with the following description of the preferred embodiment of the invention illustrated in the accompanying drawings, in which:—

Figure 1 is a view in side elevation, partly broken away, of the head of a machine constructed in accordance with the present invention; Fig. 2 is a fragmentary sectional view of a turn sole, the plane of the section extending longitudinally through the toe of the sole; Fig. 3 is a longitudinal sectional view showing the toe portion of a turn sole which has been lasted and subjected to the flap-turning and clearance-cutting operations preparatory to the turn sewing operation; Fig. 4 is a fragmentary plan view showing the channelled face of a turn sole which has been subjected to the flap turning and clearance cutting operations; Fig. 5 is a top plan view of the head of the machine shown in Fig. 1; Fig. 6 is a sectional view, taken on the line 6—6 of Fig. 5, showing the cutting tool in its retracted or inoperative position; Fig. 7 is an enlarged sectional view, taken on the line 7—7 of Fig. 5, showing the operative position of the cutting tool; and Fig. 8 is a bottom plan view of the flap turning and clearance cutting tools.

In the illustrated embodiment of the invention the flap-turning tool is indicated at 10 and the clearance-cutting tool at 12. The tools 10 and 12 are mounted for coaxial rotation in suitable bearings in a forwardly projecting portion of a head 14 which is supported by means of a standard 16. A wedge-block 18, which is interposed between the head 14 and the standard 16 serves to tilt the head rearwardly at such an angle that when the sole of the shoe is presented to the tools of the machine in a horizontal position, as indicated at 20 in Fig. 1, the common axis of the tools will be normal to the plane of the bottom of the inclined channel in the turn sole.

The flap-turning or channel-opening tool 10 comprises a hollow shaft or tube, the central portion of which is journaled in a bearing 22, that is formed in the head 14. Projecting from diametrically opposite sides of the lower exposed and slightly reduced end of the tool 10 are a pair of ribs 24 (see Fig. 8) for engaging and assisting in turning up the channel flap. As best shown in Fig. 7, the tool 10 is held against longitudinal movement in the bearing 22 by a tool-carrier 26 which is rigidly secured to the upper end of the tool, above the bearing and by a col-

lar 28 which is secured to the tool below the bearing. The tool 10 is rotated by means of a grooved pulley 30 having an upwardly extending trunnion 32 which is journaled in a bearing 34 in the head 14 above and coaxial with the bearing 22. The pulley 30 is connected to drive the tool 10 by means of two depending lugs 36 arranged diametrically opposite each other on the under side of the pulley and received in corresponding notches 38 that are severally formed in the upper ends of a pair of arms 40 rising from the tool-carrier 26. The above described construction permits the pulley 30 and the flap-turning tool 10 to be readily assembled in their respective bearings and connected to rotate together. The pulley 30 is driven by a belt 42 which passes under a pair of idler pulleys 44 at the rear of the head 14 and is adapted to be connected with any suitable source of power. As shown, the idler pulleys 44 are journaled upon the opposite ends of a horizontal axle 46 which is supported by a pair of brackets 48 rising from the opposite ends of a supporting rod 50 that is secured in a rearward projection of the head 14. Each pulley 44 is confined on the axle 46 between one of the brackets 48 and one of a pair of collars 52 which are secured to the opposite ends of the axle. A suitable guard 53 is shown secured to the bearing 22 in Fig. 1 to protect the operator from injury through coming in contact with the rotating tool-carrier 26.

The clearance-cutting tool 12 comprises an auger-like drill which is ground flat at the point and fits within a counterbored recess in the lower end of the tubular flap-turning tool 10. The sides of the cutting tool are spirally fluted or grooved to elevate within the tubular flap-turning tool the chips produced by the cutting operation. The chips are discharged through a pair of longitudinal slots 54 which are formed in opposite sides of the lower portion of the flap-turning tool. The chips are thus prevented from accumulating in the channel where they might interfere with the laying of the channel flap after the sewing operation has been completed. The cutting tool 12 is formed at the lower end of a spindle 56, the diameter of which is slightly less than that of the operative part of the tool. The spindle 56 is journaled within the tubular flap-turning tool and within an axial bearing in the pulley 30. The upper end of the spindle 56 projects above the pulley and rigidly secured thereto is a rotatable carrier-block 58 which sustains the weight of the cutting tool and is connected to be continuously driven by the pulley 30. The means for operatively connecting the carrier-block 58 with the pulley 30 comprises a pair of lugs 60 depending from the carrier block, on opposite sides of the spindle 56, which are severally re-

ceived in notches 62 in the top of the trunnion 32 of the pulley 30. These cooperating lugs and notches are arranged to permit longitudinal movement of the spindle 56 and 5 cutting tool 12 relatively to the flap-turning tool 10 for the purpose of projecting and retracting the cutting tool.

The means for imparting longitudinal movement to the cutting tool 12 comprises 10 an arm 64 which is mounted for a limited amount of vertical swinging movement above the head 14 and which is provided at its forward end with a recess 66 in which the carrier-block 58 is supported. The rear extremity of the arm 64 is forked to embrace 15 the rearwardly projecting portion of the head 14 and is pivoted on the rod 50 between the brackets 48. The arm 64 is connected with the carrier-block 58 by means of a pair 20 of studs 68 which are screw-threaded into the forward end of the arm 64 on opposite sides of the recess 66, the studs having inwardly projecting ends which enter an annular groove 70 in the carrier-block 58.

25 The cutting tool is normally maintained in retracted or inoperative position by means of a coiled spring 72 (Fig. 1) one end of which is seated in a recess 74 near the forward end of the arm 64, the opposite end of 30 the spring bears against the top of the head 14. The force of the spring 72 tends to swing the arm 64 upward and hold the cutting tool retracted. A rod 76 connects the arm 64 with a suitable foot treadle (not 35 shown) by means of which the arm may be depressed to project the cutting tool into working position (see Fig. 7). The upward movement of the arm 64 and the cutting tool 12 is limited by the engagement of a collar 40 78, which is secured to the rod 76, with a ledge 80 on the head 14. The extent of downward movement of the arm 64 and the cutting tool 12 is determined by means of a 45 stop-screw 82 which projects downwardly through the recess 74 and through the coils 50 of the spring 72 and is adapted to engage the adjacent portion of the head 14. By rotating the screw 82 the amount which the cutting tool is permitted to project beyond the flap-turning tool may be adjusted for the 55 purpose of varying the amount of material removed from the sole by the cutting operation. A lock nut 84 is provided for securing the stop-screw 82 in adjusted position.

During the cutting operation the upward thrust of the cutting tool is received by a bolt 86 which is screw-threaded into the arm 64 and projects into the recess 66 in axial alignment with the spindle 56. The bolt 86 60 may be adjusted to compensate for wear on the cutting tool and is adapted to be secured in adjusted position by a lock nut 88.

In order that the sole stock may be cut away at the proper place, a gage 92 (Fig. 1) 65 is provided to assist in locating the toe of the

sole in line with the tools of the machine. The gage 92 is adjustably secured to the forwardly projecting portion of the head 14 by means of two bolts 94. The bolts 94 extend through slots 96 which permit adjustment of 70 the gage toward and from the tool to vary the location of the cut-away portion in accordance with the size or style of the shoe.

In operating upon a turn sole by means of the present machine the operator holds 75 the lasted shoe with the sole substantially horizontal and with the toe of the sole beneath the tools of the machine, one side of the shoe being directed toward the gage 92. The shoe is then manipulated to cause the 80 flap-turning tool to enter the channel on the side toward the gage 92 at a point about one inch to the rear of the toe end of the channel. The shoe is then moved in a direction to cause the channel flap to be gradually 85 turned back until the point of the toe is reached. The flap-turning tool rotates in a clockwise direction, viewed from above, and the ribs 24 are brought in rapid succession into engagement with the inner face of the 90 channel flap, causing the flap to be turned into upright position, as indicated at 98 in Figs. 3 and 4. The beating action of the ribs 24 against the channel flap effectively turns up the flap and sets it in upturned 95 position, so that there will be no tendency for it to spring back and close the channel when the sole is removed from the machine. When the shoe has been moved into such a position that the portion of the sole which 100 is to be cut away is directly beneath the cutting tool, the operator swings the shoe so that the rounded portion of the upper adjacent to the sole edge at the extreme point of the toe bears squarely against the gage 92. 105 This determines the exact location of the cut by positioning the point to be operated upon in line with the cutting tool. The operator then depresses the foot treadle thus 110 projecting the cutting tool into operative position. The action of the cutting tool removes the portion of the body of the sole between the channel cuts at the point of the toe. The portion of the sole which is thus removed by the cutting tool is indicated by 115 dotted lines at 100 in Fig. 3. The cutting operation enlarges the channel at the toe end of the sole, as shown clearly in Fig. 3, so as to provide clearance space for the channel guide during the operation of sewing around 120 the toe in the turn sewing machine. After this portion of the sole stock has been cut away by the cutting tool, the operator releases the foot treadle causing the cutting tool to be immediately retracted by the 125 spring 72 into inoperative position. The shoe is then manipulated relatively to the flap-turning tool so that a portion of the channel flap is turned up at the opposite side of the toe portion of the sole, and the 130

shoe is then removed from the machine. At the completion of the operation upon the sole, the sole is prepared as illustrated in Figs. 3 and 4, which indicate clearly the appearance of the up-turned channel-flap and show the result of the cutting operation which provides the necessary clearance space for the channel guide.

By supporting the sole operating tools at the angle indicated in Fig. 1, the sole of the shoe may be always held in a substantially horizontal position, which is most convenient for the operator, and furthermore permits the operator readily to observe the point of operation of the tools. The inclined cutting face of the clearance cutting tool tends to minimize the extent to which the sole is cut away and therefore prevents undue weakening of the sole by the clearance-cutting operation. The action of the flap-turning tool is useful in pushing aside pulling-over and lasting tacks which may have been driven too far inwardly, thus preventing them from constituting obstructions in the path of the channel guide.

While the particulars of the construction herein set forth are well suited to one form of the invention, it is to be understood that these particulars are not essential since they may be variously modified within the skill of the artisan without departing from the true scope of the actual invention as defined by the following claims.

What is claimed as new, is:—

- 35 1. A machine for operating upon the soles of lasted turn shoes just after the first lasting operation, comprising coaxial channel opening and stock removing tools capable of performing their functions simultaneously, and a fixed gage having a smooth flat face against which the operator may press the rounded portion of the upper at the tip of the toe to locate the channel relatively to said tools.
- 40 2. In a machine for operating on lasted turn shoes just after the first lasting operation, in combination, a stock-fitting tool, and a gage to engage the rounded portion of the upper at the tip of the toe of a lasted turn shoe to position the shoe to locate the channel of its sole relatively to said tool.
- 45 3. A machine for operating on channeled soles comprising, in combination, means for removing material from a sole between the converging sides of the channel at the toe without injuring the channel flap, and means to position a sole to be operated on thereby.
- 50 4. A machine for operating upon soles comprising means for cutting away a portion of the sole stock between the converging inner edges of the channel at the point of the toe, and means to engage the channel flap and protect it from the action of the cutting means.
- 55 5. A machine for operating upon soles

having, in combination, a drill for cutting away a portion of the sole stock between the channel cuts at the point of the toe, and a member to engage the channel flap and guard it from the action of the drill.

6. A machine for operating upon turn soles having, in combination, a housing, a cutting tool, normally retracted within the housing, for removing a portion of the sole stock between the channel cuts at the point of the toe of a sole, means for locating the toe of the sole in position to be acted upon by said tool, and controllable means for projecting the cutting tool into working position.

7. A machine for operating upon turn soles having, in combination, a rotatable cutting tool for cutting away a portion of the sole stock between the channel cuts at the point of the toe of a sole, said tool having a lateral spiral groove for elevating the chips produced by the cutting operation, a housing for said tool having a lateral opening to permit the discharge of the chips, and means for locating the point of the toe of the sole in line with said tool.

8. In a machine for operating upon turn soles, means for turning up the channel flap, and means for removing a portion of the sole stock between the channel cuts at the point of the toe comprising a drill having an end cutting edge.

9. A machine for operating upon turn soles comprising a tool for turning up the channel-flap and enlarging the channel at the toe of the sole to provide clearance for the channel guide during the operation of sewing around the toe, and a gage for locating the work relatively to said means.

10. A machine for operating upon turn soles having, in combination, means for turning up the channel-flap, and means for cutting away a portion of the sole stock between the converging inner edges of the channel at the point of the toe.

11. A machine for operating upon turn soles having, in combination, a tool for turning up the channel-flap, and a rotatable cutter for cutting away a portion of the stock in the body of the sole at the toe.

12. A machine for operating upon turn soles having, in combination, a tubular tool for turning up the channel flap at the toe of the sole, and a cutting tool disposed within the flap-turning tool for cutting away a portion of the sole stock at the toe.

13. A machine for operating upon turn soles having, in combination, a rotatable tool for turning up the channel flap, a rotatable tool for cutting away a portion of the sole stock between the channel cuts at the point of the toe mounted to rotate coaxially with the flap-turning tool, and means for rotating said tools.

14. A machine for operating upon turn

5 soles having, in combination, means for turning up the channel flap at the toe of the sole; a normally inoperative cutting tool for removing a portion of the stock at the toe of the sole, and controllable means for rendering the cutting tool operative.

10 15. A machine for operating upon turn soles having, in combination, a tubular tool for turning up the channel flap at the toe of the sole, a cutting tool normally retracted within the flap-turning tool for cutting away a portion of the stock at the toe of the sole to provide clearance for the channel guide during the turn sewing operation, and controllable means for projecting the cutting tool into working position.

15 20. A machine for operating upon turn soles having, in combination, a rotatable tool for turning up the channel flap, an axially mounted rotatable cutting tool for cutting away a portion of the sole stock between the channel cuts at the point of the toe, means for normally holding the latter tool nested within the former, and means for projecting the latter tool into working position at the will of the operator.

25 30. A machine for operating upon turn soles having, in combination, a tubular rotatable tool for turning up the channel flap at the toe of the sole, a rotatable cutting tool coaxially disposed and normally retracted within the flap-turning tool for cutting away a portion of the stock at the toe of the sole to provide clearance for the channel guide during the turn sewing operation, means for rotating the tools, and means for projecting the cutting tool into working position.

35 40. A machine for operating upon turn soles having, in combination, a tubular rotatable tool for turning up the channel flap at the toe of the sole, a rotatable cutting tool coaxially disposed and normally retracted within the flap-turning tool for cutting away a portion of the stock at the toe of the sole to provide clearance for the channel guide during the turn sewing operation, means for rotating the tools, and means for adjusting the amount of projection of the cutting tool to vary the amount 45 of stock removed from the sole by the cutting operation.

45 50. A machine for operating upon turn soles having, in combination, a frame, a tubular rotatable tool journaled in the frame for turning up the channel flap at the toe of the sole, a normally retracted rotatable cutting tool coaxially arranged within the flap-turning tool and adapted for longitudinal movement relatively to the latter, controllable means comprising an arm pivoted to the frame and operatively connected with the cutting tool for imparting longitudinal movement to the latter to project it into working position, and a spring for returning the cutting tool to retracted position.

55 60. A machine for operating on shoes comprising, in combination, a plurality of coaxial stock-fitting tools adapted to perform their respective functions simultaneously on a shoe, mechanism to rotate said tools about their common axis, and means to move one of the tools axially to and from operative position, the other of said tools being constructed and arranged to remain constantly in operative position. 75

65 70. A machine for use in making shoe comprising, in combination, a rotary tool having a hollow cylindrical portion about its axis and having an opening therethrough intersecting said portion, and a drill mounted within said hollow portion to rotate about the same axis and having spiral portions to elevate waste material and eject it through said opening. 80

75 80. A machine for use in making shoes comprising, in combination, a continuously-operating stock-fitting tool having a hollow portion, a second stock-fitting tool in said hollow portion, said tools being adapted to perform their respective stock-fitting operations simultaneously, and manually-controlled means to move said second tool to and from operative position during the operation of said first tool so that the first tool may be operated alone or both tools simultaneously at the will of the operator. 90

85 90. A machine for use in making shoes comprising, in combination, a perforated rotatable hollow member and a stock-removing tool within said member and arranged to eject waste stock through the perforation therein and to rotate about the same axis, and manually-controlled means to move the tool axially to and from operative position. 100

95 100. A machine for use in making shoes comprising, in combination, a hollow cylindrical casing, a cylindrical tool mounted within the hollow casing to rotate about its axis, a manually controlled lever for projecting the tool beyond the casing and for withdrawing it, and a gage adjacent the casing with a guiding surface parallel to said axis. 110

105 110. A tool for use in preparing the soles of pointed shoes for sewing comprising, in combination, means to push back the channel flap at the toe, and means to remove sole stock from between the converging sides of the channel to provide clearance for the channel guide of the sewing machine. 115

115 120. A tool for operation on the sole of a pointed shoe held in the hand of an operator to prepare it for sewing the sole to the upper, comprising, in combination, a cutter to remove stock between the converging sides of the channel at the toe of the sole of the shoe to provide clearance for the channel guide of the sewing machine, and means engaging the channel flap to prevent mutilation thereof by the cutter. 125

27. In a machine for operating on lasted shoes, in combination, means for turning up the channel flap at the toe of a shoe, means for enlarging the channel at the toe while said flap turning means is operating, a work gage having a gaging surface disposed in parallel relation to the axis of the tool for determining the location of the channel en- larging tool with respect to the work, said gage being mounted for adjustment toward and from the tool, and means associated with the gage for maintaining the parallel relation of its gaging surface with the tool axis in various positions of adjustment. 10

FREDERIC E. BERTRAND.
